UNITED STATES PATENT OFFICE.

ANATOLE PANALLE, OF NEW ORLEANS, LOUISIANA, ASSIGNOR OF ONE-FOURTH TO
LEWIS R. LESTER, OF NEW ORLEANS, LOUISIANA.

BATHING SUIT.

Application filed April 27, 1921. Serial No. 464,778.

To all whom it may concern:

Be it known that I, ANATOLE PANALLE, a citizen of the United States, residing at New Orleans, in the parish of Orleans and 5 State of Louisiana, have invented new and useful Improvements in Bathing Suits, of which the following is a specification.

My present invention pertains to safety bathing suits, and it contemplates the provision in a bathing suit of the type set forth, of means whereby when the suit is worn by a bather, the pouches thereof will be automatically inflated to prevent sinking of the wearer when in the water.

10 The invention further contemplates the provision of automatically inflated pouches that are so constructed and arranged that the bathing suit to which they are attached may be readily and easily folded when desired.

15 The invention in all of its details will be fully understood from the following description and claim when the same are read in connection with the drawings accompanying and forming part of this specification, in which:—

Figure 1, is a rear elevation of my novel safety bathing suit.

Figure 2, is a front elevation thereof.

30 Figure 3 is a longitudinal section of a portion of one leg of the device and one safety attachment secured thereto.

35 Figure 4 is a view showing one safety attachment compressed to the position it assumes when the bathing suit is folded.

Figure 5 is a detail view of one of the ribs of the safety attachment.

Similar numerals of reference designate corresponding parts in all of the views of 40 the drawings.

My safety device is secured to a bathing suit 1 of any type, but preferably of the one-piece construction illustrated.

45 The safety attachment comprises a pouch 2 of air and water-proof material 3 and the said pouch is provided with an upper wall 4 and a lower wall 5. These walls 4 and 5 by preference terminate in points as shown in Figure 1 and the pouches are secured by stitching or otherwise to the front of the bathing suit as indicated by 6.

50 The pouches 2 are preferably of triangular shape and secured with the pouches by stitching or other fastening means 8 are 55 ribs 7 of metal or other suitable material.

The ribs are of the shape indicated in Figure 5 and are equi-distantly arranged as shown within the pouches 2 and are so constructed and arranged that the pouches will be retained in open position when the bathing suit is being worn but said ribs 7 are also adapted to be folded in a small neat bundle as indicated by Figure 4 when occasion demands.

When a suit equipped with my novel safety attachment is donned by a bather, naturally the pouches will assume the position shown in Figures 1 and 2. This will cause the pouches to become buoyant when the same strikes the water and hence the device acts automatically to prevent sinking of the bather.

50 A tube 5' is arranged in the lower end of the pouches whereby they may be inflated and deflated when desired.

55 It will be gathered from the foregoing that the device is simple and inexpensive to produce and through its use a bather may enter any depth of water with safety even though he or she may be unable to swim.

Manifestly any number of the devices 60 may be installed on board of a ship in a small space and in case of necessity may be donned with facility by a passenger.

Having described my invention, what I 65 claim and desire to secure by Letters-Patent is:—

In a safety device for bathing suits, the combination of a member formed of a single piece of water and air proof material and having upper and lower walls adapted to be securely fastened to a bathing suit, ribs in triangular shape in cross-section adapted to be fastened at equi-distant points within the member whereby it will assume a triangular appearance with respect to the bathing suit; said ribs being further constructed to bear one upon the other when the suit is folded, and means arranged in the lower end of the member for inflating the same.

70 In testimony whereof I have hereunto set my hand in presence of two subscribing witnesses.

ANATOLE PANALLE.

Witnesses:

A. R. BEARY,
M. SIMPSON.
